IGNITION-CONTROLLING SWITCH.

1,354,902.

Specification of Letters Patent.

Patented Oct. 5, 1920.

Application filed March 7, 1918. Serial No. 221,063.

To all whom it may concern:

Be it known that I, VALÈRE A. FYNN, a subject of the King of England, residing at the city of St. Louis, State of Missouri, United States of America, have invented a certain new and useful Ignition-Controlling Switch, of which the following is such a full, clear, and exact description as will enable any one skilled in the art to which it appertains to make and use the same, reference being had to the accompanying drawings, forming part of this specification.

My invention relates to a switch for controlling the ignition circuit of an internal combustion engine and is more particularly adapted to be used in connection with a battery ignition system.

The object of the invention is to automatically disconnect the source of energy from the ignition circuit, when the engine speed falls below its lowest operating speed or when the engine comes to rest.

My invention will be better understood by reference to the accompanying diagrammatic drawings, in which Figure 1 shows one form of my improved ignition switch as applied to a battery ignition, starting and lighting system for use on automobiles, while Fig. 2 is an explanatory diagram; Fig. 3 illustrates a modification.

In a battery ignition system, the current taken by the spark coil varies greatly according to the speed at which the timer is driven. The speed of the timer depends on the speed of the engine. With the engine standing still, the current taken by the spark coil is a maximum. As the speed increases, this current diminishes rapidly at first, and then slowly, as indicated by curve 33 of Fig. 2. The slow change in the current takes place at speeds exceeding the lowest operating speed of the engine. This speed is, as a rule, only a small per cent. of the maximum speed at which the engine runs in normal operation, as indicated by the dotted lines 34 and 35 of Fig. 2, where the line 34 marks the lowest and the line 35 the maximum speed of an internal combustion engine, selected as an example. The rapid diminution of the current taken by a spark coil is, in the main, due to the circuit interruption caused by the timer. These interruptions produce the same effect as a change in the impedance of the circuit. As long as the engine revolves, the current in the ignition circuit is a pulsating one, the

frequency of the pulsations being proportional to the speed.

It is apparent from Fig. 2, that a coil which is designed to operate near the safe temperature limit under normal working conditions, is very liable to become overheated and damaged in case the ignition circuit is not interrupted after the engine comes to a stand-still. In such case the coil will be subject to an abnormal and excessive current and the drain on the battery may be so great as to entirely discharge same in a short space of time. My improved ignition switch is adapted to prevent the occurrence of these conditions.

In carrying out this invention, I provide an electromagnetic ignition switch, which is normally open but which can be closed by hand or by energizing one of its magnetizing windings and which opens automatically as soon as the frequency of the current interruptions in the ignition circuit has fallen below a predetermined limit or has become zero and the current in said circuit has reached a predetermined value. In the embodiment herein described, this switch has a spring controlled contact-carrying armature coöperating with an electromagnet provided with a shunt winding, a series winding, and a short-circuited winding. The spring tends to keep the armature away from the electromagnet and holds the ignition circuit open. The shunt winding is adapted to be connected to the battery and carries a constant current when its circuit is completed. Its circuit is normally open, but is completed when the ignition switch is closed. The series winding is included in the primary or low tension ignition circuit, and, therefore, carries a pulsating current when the engine revolves and a constant unidirectional current when the engine is at rest and the ignition circuit closed. The series winding is connected to oppose the magnetization produced by the shunt winding, and the number of its turns is so chosen that the magnetization of the shunt winding is equaled when the engine is not running or is revolving at a speed below its lowest operating speed.

Since the ignition switch should not be closed until the engine is cranked to start it, I prefer to so arrange the circuit closing switch of the starting motor that when it closes the starting circuit, it also closes the

circuit of the shunt winding on the automatic switch. The closing of the shunt winding circuit closes the ignition switch, which completes the ignition circuit when the timer is closed. When the engine fires and the starting switch is released, the shunt winding, the circuit of which is now also closed through the contacts of the ignition switch, remains closed as long as the engine speed keeps above the critical or that for which the automatic switch is set to open.

In order to minimize the effect of the ignition current in the series winding of the automatic switch at high speeds and increase it at low speeds, and also in order to reduce the impedance of the series winding to a minimum, I provide a short-circuited winding on the automatic switch, and place same in the closest possible inductive relation to the series winding. This short-circuited winding will not have any effect on the magnetization produced by the shunt winding when said winding is connected to produce a constant magnetization, but it will tend to suppress the magnetizing effect of the rapidly varying current in the series winding. This screening effect will diminish with decreasing frequency of the variations of the current and will disappear entirely when the current interruptions cease.

In Fig. 1 the storage battery 8 is permanently connected to the main 36 of the lighting circuit comprising the lamps 31 and can be connected to the other main 37 of said circuit by means of the switch 30. The battery is also permanently connected to one pole of the direct current engine driven lighting and charging generator 23, 24. This generator is adapted to be connected to the other pole of the battery by means of a battery switch 27 of known construction, which closes when the generator voltage reaches a certain value and opens when said voltage falls below the battery voltage. When this automatic battery switch is closed the generator and the battery coöperate in a well known manner, the generator charging the battery and supplying such consumption circuits as are connected, or the consumption circuit or circuits receive part of their energy from the battery and part of it from the generator.

The high tension winding 4 of the ignition circuit is grounded at one end and connected to the engine driven distributor 5 at the other. This distributor is adapted to connect the winding 4 to the spark plugs 6 in the usual way.

The low tension ignition circuit can be traced from the positive pole 41 of the battery 8 through the winding 3 of the spark coil, the timer 7 and back to the negative pole of the battery in one of three paths. Either by way of the spring controlled normally open switch 40, or by way of the

spring controlled and normally open starting switch 10 and the contacts 11, 12 thereof, or by way of the contacts 17, 18 of the automatic ignition switch 16, the series winding 14 on said switch and the spring controlled 70 and normally closed switch 39.

The automatic ignition switch also carries a shunt winding 15, one end of which is permanently connected to the positive pole of the battery, while the other end can be connected to its negative pole without passing through the timer 7, and either by way of the normally closed switch 39, the winding 14 of the automatic ignition switch and the contacts 17, 18 thereof, or by way of the starting switch 10 and its contacts 11, 12, or through the normally open switch 40.

The timer 7 is operated in the usual way by means of an engine driven cam. When the engine is at rest, this timer may be open or closed, depending on the position in which the engine comes to rest.

Switch 39 is intended to be operated by hand, the spring controlling same tending to keep it closed. The switch 40 is also arranged for hand operation, the spring controlling it tending to keep it open. The starting switch 10 is normally held open by means of the spring 9. It can be closed by hand, in which case it not only connects one end of the shunt winding 15 to the negative pole of the battery 8, but also completes the circuit of the cranking motor 21, 22 which is suitably geared to the engine and one pole of which is permanently connected to the positive pole of the battery.

The automatic ignition switch comprises a stationary magnet core 20 and a movable switch arm 16 pivoted at 19 and provided with an armature adapted to coöperate with the core 20 and carrying a pair of movable contacts adapted to coöperate with a couple of stationary ones 17, 18. When two groups of contacts are used one is arranged to close before and to open after the other and may be provided with a tip adapted to withstand arcing, such as carbon tips, for example. One group of contacts may be used instead of two. In addition to the shunt winding 15 and the series winding 14, the core also carries a permanently short-circuited winding 38, diagrammatically shown as a single closed loop. In practice one would use a more efficient form of short-circuit, such for instance as a solid copper cylinder surrounding the core 20 and located under the series coil 14.

The operation of the improved ignition switch in connection with the starting, lighting and ignition system with which it is illustrated in Fig. 1 is as follows:

With the engine at rest, the timer 7 may be open or closed. The battery switch 27, the starting switch 10 and the auxiliary switch 40 will be open, the switch 39 will be

closed and we will assume the automatic switch 16 to be open. If the engine is to be cranked by hand, the auxiliary switch 40 is held closed until the engine fires. The closing of this switch completes the circuits between the battery and the winding 15 of the switch 16 causing said switch to close. This places the timer in control of the ignition circuit. As the engine is revolved, the winding 14 is energized by the ignition current. When the engine fires and reaches its idling speed or exceeds same, the switch 40 may be released without fear of the switch 16 opening because the magnetization produced by 14 will, under the circumstances, not be sufficient to reduce the total magnetization of the core 20 to a point where it will release the spring controlled armature with which it cooperates.

If the engine fails to start and the switch 40 is released after the engine comes to rest, the automatic switch will stay closed if the timer has stopped in its open position and there will be a drain on the battery to the extent of the small current taken by the winding 15. If the timer stops in its closed position and the switch 40 is not released after the engine has come to rest, then the automatic switch will vibrate until switch 40 is opened when the automatic switch will open and stay open. In case the engine has come to rest with the timer 7 open and the automatic switch has in consequence remained closed, it may be opened by momentarily opening switch 39; it will open automatically if the engine is moved in any way so as to close the timer, even for a short period.

If the engine is to be cranked by means of the motor 21, 22, then switch 10 is closed, whereby the circuit of the cranking motor and the circuit of the shunt winding 15 are both completed. The operation is otherwise the same as explained in connection with switch 40.

After the engine has reached a sufficient speed, the battery switch 27 closes, but this makes no difference to the operation of the automatic switch 16. When it is desired to stop the engine, it is only necessary to open switch 39 and hold it open for a brief space of time.

By placing the timer 7 in a position within the ignition circuit in which it will interrupt the current through the series winding 14, but not through the shunt winding 15 of the automatic switch, I make the magnetizing value of the current through the winding 14 dependent on the engine speed. This current is then fully effective at zero engine speed, but its effectiveness diminishes with increasing speed for the reason that its periodicity increases, thus making the shielding effect of Foucault currents more and more pronounced. Such currents are set up in the core 20 and more particularly

in the short-circuited winding 38. The fact that the magnetizing effect of the pulsating current in 14 diminishes with increasing engine speed, tends to make the automatic switch all the more sensitive at speeds below the lowest operative engine speed.

By locating the timer between the winding 15 and the negative pole of the battery 8, as shown in Fig. 3, said timer will interrupt the current through the winding 15 as well as through the winding 14, and the current in both of the windings will be pulsating as long as the engine revolves. The switch will operate as before except that the automatic switch will not stay closed in case the engine stops with the timer open and switch 40 or switch 10 is not released until after the engine has come to rest. The reason for this change is that an open timer located in this alternative position interrupts the current through the winding 15 as well as through the winding 14.

Having fully described my invention, what I claim as new and desire to secure by Letters Patent of the United States is:

1. In an ignition system, a primary ignition circuit comprising a source of current, an ignition timer and a circuit controlling switch, magnetic means normally holding said switch in closed position and means responding to abnormal current in the primary ignition circuit to cause the switch to open.

2. In an ignition system, a primary ignition circuit comprising a source of current, an ignition timer and a circuit controlling switch, magnetic means normally holding said switch in closed position, and means responding to abnormal current in the primary ignition circuit to render the holding means ineffective.

3. In an ignition system, a primary ignition circuit comprising a source of current, an ignition timer and a circuit controlling switch, means operated from the source of current for normally holding said switch in closed position, and means responding to abnormal current in the primary ignition circuit to render the holding means ineffective.

4. In an ignition system, a primary ignition circuit comprising a source of current, an ignition timer and a circuit controlling switch, magnetic means normally holding said switch in closed position, means responding to abnormal current in the primary ignition circuit to cause the switch to open, and an auxiliary switch for opening the primary ignition circuit.

5. In an ignition system, a primary ignition circuit comprising a source of current, an ignition timer and a circuit controlling switch, magnetic means normally holding said switch in closed position, means responding to abnormal current in the primary ignition circuit to cause the switch to

open, and an auxiliary switch for opening the primary ignition circuit, said switch being normally held in closed position.

6. In an ignition system, a primary ignition circuit comprising a source of current and an ignition timer, a switch controlling said circuit and magnetic means for operating said switch, said means comprising two windings connected to produce opposing magnetizations, one of said windings being in series circuit with the timer when the switch is closed.

7. In an ignition system, a primary ignition circuit comprising a source of current and an ignition timer, a switch controlling said circuit, magnetic means for operating said switch; said means comprising two windings connected to produce opposing magnetizations, one of said windings being in series circuit with the timer when the switch is closed, and means for connecting the other winding in circuit with the source of current to close the switch.

8. In an ignition system, a primary ignition circuit comprising a source of current and an ignition timer, a switch controlling said circuit, magnetic means for operating said switch, said means comprising two windings connected to produce opposing magnetizations, both of said windings being in circuit with the source of current when the switch is closed and one of the windings being in series circuit with the timer.

9. In an ignition system, a primary ignition circuit comprising a source of current and an ignition timer, a switch controlling said circuit, magnetic means for operating said switch, said means comprising two windings connected to produce opposing magnetizations, one of said windings being connected to the source of current in series with the timer and the other winding being connected to said source in shunt with respect to the timer circuit.

45 10. In an engine starting and ignition system, a primary ignition circuit comprising a source of current, an ignition timer and a circuit controlling switch, a starting motor and a starting switch therefor, and means for closing the controlling switch and holding it closed, said means being controlled by the starting switch when the controlling switch is open and by the controlling switch when said switch is closed.

55 11. In an engine starting and ignition system, a primary ignition circuit comprising a source of current, an ignition timer and a circuit controlling switch, an electro-

magnet for closing said switch and holding it closed, said magnet being provided with 60 a shunt exciting winding, means for connecting said winding in circuit with the source of current to close the controlling switch, and other means making connection between said winding and said source when 65 the controlling switch is closed.

12. In an ignition system, a primary ignition circuit, a source of current therefor and a switch controlling said circuit, magnetic means for operating said switch comprising two windings connected to produce opposing magnetizations, one of said windings being connected to the source of current to receive a substantially constant current, and the other winding being connected 75 to receive current varying with the current in the ignition circuit.

13. In an ignition system, a primary ignition circuit comprising a source of current, an ignition timer and a controlling switch, 80 and an electromagnet for operating said switch, said magnet being provided with a shunt winding, a short-circuited winding and a series winding.

14. In an ignition system, a primary ignition circuit comprising a source of current, an ignition timer and a controlling switch, and an electromagnet for operating said switch, said magnet being provided with a shunt winding, a short-circuited 90 winding and a series winding, said last named winding being in circuit with the ignition timer when the ignition controlling switch is closed.

15. In an ignition system, a primary ignition circuit, a switch for controlling said circuit, magnetic means for operating said switch comprising two windings, means for impressing a substantially constant potential on one of said windings, and means for supplying to the other winding a current of varying frequency.

16. In an ignition system, a primary ignition circuit, a switch for controlling said circuit, magnetic means for operating said switch comprising two windings, means for impressing a substantially constant potential on one of said windings, means for supplying to the other winding a current of varying frequency, and means for reducing the magnetizing effect of said last named winding with increasing frequency.

In testimony whereof I have hereunto set my hand and affixed my seal.

VALÈRE A. FYNN. [L.S.]
